[57] **ABSTRACT**

Hydrazine is catalytically decomposed in a primary reaction chamber. During low thrust operation all of the decomposition products flow directly to the nozzle. During high thrust operation an oxidizer is reacted with a major portion of the decomposed hydrazine in the central portion of the secondary reaction chamber downstream of the primary reaction chamber. The remaining decomposed hydrazine is directed as a buffer layer along the inner surface of the secondary reaction chamber's outer wall, to serve as a coolant.

TWO-STAGE HYDRAZINE ROCKET MOTOR

BACKGROUND OF THE INVENTION

1. Field of the Invention

This invention relates to gas generators such as in rocket propulsion systems, and more particularly to a two-stage propulsion system which uses the reacted products of a monopropellant first stage as both a propellant and a coolant for a bipropellant second stage.

2. Description of the Prior Art

Hydrazine in bipropellant rocket engines has been considered an advantageous fuel because of its high performance and its favorable storage and handling characteristics. The primary difficulties heretofore encountered in the use of liquid hydrazine in bipropellant engines are that the explosive thermal decomposition property of hydrazine has seriously limited its use as a reliable regenerative coolant and that the liquid injection of the propellants, such as hydrazine and nitrogen tetroxide frequently result in rough starting transients and combustion instability. One technique of improving the ignition characteristics of these propellants has been to substitute for the hydrazine another propellant, such as Aerozine 50 ($N_2H_4/UDMH$) or MMH. Unfortunately, however, these hydrazine-substitutes produce lower specific impulse than hydrazine. In addition, hydrazine is already being more widely used as a monopropellant for attitude control and gas pressurization systems and therefore it is highly desirable to avoid using a hydrazine-substitute so as to eliminate the need for a third storage facility aboard the space vehicle.

Another technique for using hydrazine as the main fuel has been to decompose the hydrazine to produce first stage thrust and to introduce an oxidizer into the products of decomposition to produce a higher secondary stage thrust. In this case the products of decomposition, N_2 , N_2 , NH_3 readily react with the oxidizer, N_2O_4 or F_2 , for example, to produce the desired high performance and thus eliminate the use of a hydrazine-substitute and its storage facility. Such a technique is shown, for example, in the United States patent to LaRocca, U.S. Pat. No. 3,149,460, granted Sept. 22, 1964.

In the reaction between the hydrazine decomposition products and an oxidizer an enormous quantity of heat is generated. The thrust chamber walls and nozzle in order to be protected must either be manufactured of heat resisting materials, lined with ceramic materials or the like, cooled by passing a coolant through or over them, or combinations of these.

One technique for cooling reaction chamber walls is shown in the United States patent to Grow, U.S. Pat. No. 2,706,887, granted Apr. 26, 1955. In this patent an annular liner is placed in the reaction chamber and one of the propellants is introduced inside and outside of the liner. The propellant introduced inside the liner is reacted with a second propellant producing high temperature reaction products. The propellant introduced outside the annular shield is decomposed in such outer chamber to produce a lower temperature motive fluid.

SUMMARY OF THE INVENTION

This invention pertains to a two-stage rocket motor which employs a primary reaction chamber in which hydrazine is catalytically decomposed, and a secondary

reaction chamber in which the hydrazine products of decomposition may be reacted with an oxidizer.

According to the invention, the products of hydrazine decomposition may be used alone to provide low energy propulsion and reacted with the oxidizer to provide high energy propulsion. Also, during the secondary reaction some of the products of hydrazine decomposition are advantageously used as a film coolant for the side wall of the secondary reaction chamber.

BRIEF DESCRIPTION OF THE DRAWING

FIG. 1 is a view partially in side elevation and partially in longitudinal section of a two-stage rocket motor employing the principles of the invention;

FIG. 2 is a transverse sectional view taken substantially along line 2—2 of FIG. 1, with a portion of the oxidizer injector cut away; and

FIG. 3 is a fragmentary view, also partially in side elevation and partially in longitudinal section, of a modified form of two-stage rocket motor.

DESCRIPTION OF THE PREFERRED EMBODIMENTS

The illustrated embodiment comprises an outer tubular wall 12 of stainless steel or the like defining an internal space which is divided axially into a first stage or primary reaction chamber 14 and a second stage or secondary reaction chamber 16. Wall 12 is provided with a peripheral flange 18 to which is secured a rocket nozzle 20, also of stainless steel or the like, which may be of conventional design.

A conduit 22 leads from a source of liquid hydrazine to a multiported injector incorporated into the upstream wall 26 of the primary reaction chamber. In the illustrated embodiment a plurality of conduits 24 extend from a source of an oxidizer, such as nitrogen tetroxide, to and then axially through the primary reaction chamber 14.

The first stage reaction chamber 14 is divided into two parts by a perforated screen or plate 28. The upstream part contains fine catalyst particles and the downstream part contains coarser catalyst particles.

Reaction chamber 14 has a perforated downstream wall 32. A screen 30 is located inside of wall 32 for retaining the catalyst particles within chamber 14. Wall 32 is provided with a plurality of central openings 31, a plurality of intermediate openings 33, and a plurality of outer openings 34. The outer openings 34 are directed to discharge adjacent an inner surface portion of wall 12.

The second stage reaction chamber 16 may include an annular liner 36 (e.g., of a refractory material) which is spaced radially inwardly of outer wall 12, so as to leave an annular space between the liner 36 and the outer wall 12. In other embodiments (not shown) this liner may be omitted.

An annular oxidizer injector 37 is centrally positioned within the second stage reaction chamber, and is connected to the conduits 24 leading from the supply of liquid oxidizer. In FIGS. 1 and 2 the outlet ports 39 of injector 37 are shown to discharge radially outwardly into the annular zone surrounding injector 37, for mixing contact in such zone with hydrazine decomposition products. In a linerless embodiment the outlet ports 39 would be directed generally axially.

In operation, liquid hydrazine is delivered into the first stage reaction chamber 14 and decomposes therein, forming hot gaseous nitrogen, hydrogen and ammonia, the temperature of which is about of 1,600° F. The main portion of these gases passes through the openings 31, 33 in wall 32. During single stage operation all of the decomposed hydrazine flows directly to the nozzle 20. When higher thrust capability is required, the gases exiting the openings 33 are mixed with the oxidizer (e.g., nitrogen tetroxide (N_2O_4) which is introduced through the injector 37. The second stage reaction between the hydrazine gases and the oxidizer results in an increase in the chamber gas temperature to approximately 5,000° F depending upon the oxidizer used. The decomposed but relative cool (viz. about 1,600° F) hydrazine which flows through openings 34 in wall 32 into the space between the liner 36 and the wall 12 insulates the outer wall 12 and the nozzle 20 from the high temperature in the central zone.

During operation, the pressure drop of the gases within chamber 14 exerts a force which tends to buckle wall 32 outwardly. Preferably the conduits 24 are anchored at their ends so that they can provide support for wall 32.

In the embodiment shown in FIG. 3 the basic structural configuration is the same as that shown in FIG. 1. However, the oxidizer is directed through a conduit 24a which passes laterally through the outer chamber wall 12 and the liner 36, into an injector 37 spaced downstream of wall 32, and from injector 37 spaced downstream of wall 32, and from injector 37 into the secondary reaction chamber.

Many space vehicles have propulsion requirements that require an engine to function not only in steady state, but also in pulse mode operation. Delivered specific impulse of conventional bipropellant engines is generally low during pulse mode operation especially for small impulse bits. Using the dual mode feature of the two-stage hydrazine rocket motor concept, the thruster can be operated as a monopropellant engine during pulse mode, and as a bipropellant during steady state; thus delivering relatively high specific impulse during both modes of operation. The Biplex system is significantly lighter than the conventional bipropellant system, especially for missions which require small impulse bits during pulse mode operation.

Principal advantages of the engine of this invention include:

1. The start transient and combustion characteristics are inherently smoother due to the fact that only atomization and vaporization of the oxidizer are required for combustion to occur. This feature eliminates the problem of destructive ignition transients due to the accumulation of unburned or partially reacted fuel constituents. 2. The relatively cool decomposition products (approximately 1,600° F) can be effectively used for cooling the thrust chamber and exhaust nozzle. 3. The capability exists for operating as either a bipropellant or monopropellant engine with attendant dual thrust level. This redundancy also results in an increase in system reliability in that, should a failure occur in the oxidizer feed system, operation in the monopropellant mode can be maintained at reduced thrust and total impulse levels. With valve modulation a greater throttling range with greater reliability can be obtained. 4. Due to the unique chamber and nozzle cool-

ing capability, and the relatively simple injector elements, it is anticipated that low cost rocket engines in a wide range of thrusts can be developed. 5. System flexibility can be achieved through use of common hydrazine propellant tanks for both the main engine and attitude control system. This is attractive from a systems viewpoint since significant deviations from a nominal mission can be accommodated by changing the propellant allocations for the attitude control system and the main engine.

While two forms of the invention have been illustrated various other modifications will be apparent to those skilled in the art. The details disclosed therefore are not to be construed as limitations on the invention.

What is claimed is:

1. A gas generator comprising:
a primary reaction chamber;
a secondary reaction chamber downstream of said primary reaction chamber defined by wall means comprising at least one tubular wall;
means for introducing a primary reactant into said primary reaction chamber;
means in said primary reaction chamber for reacting said primary reactant to produce relatively low temperature but combustible discharge products;
means for introducing a first portion of said discharge products into an inner region of said secondary reaction chamber to serve as a reactant, and a second portion as a continuous annular stream along said tubular wall, to function as a coolant; and
means for introducing a second reactant into said inner region of said secondary reaction chamber, in a zone laterally inwardly of the coolant, for reacting with the discharge products in such zone to cause a higher temperature reaction.

2. The gas generator defined by claim 1, wherein said reacting means in said primary reaction chamber includes a catalyst and said primary reactant comprises hydrazine.

3. The gas generator defined by claim 1, wherein said second reactant is an oxidizer.

4. The gas generator defined by claim 1, wherein in addition to said tubular wall said secondary reaction chamber wall means includes a tubular liner separating the higher temperature reaction zone from the chamber wall coolant, said liner is spaced radially inwardly from said tubular wall, and said annular coolant stream flows between such wall and said liner in contact with both.

5. A gas generator comprising:
a primary reaction chamber;
a secondary reaction chamber downstream of said primary reaction chamber;
means for introducing a primary reactant into said primary reaction chamber;
means in said primary reaction chamber for reacting said primary reactant to produce relatively low temperature but combustible discharge products;
means for introducing said discharge products into said secondary reaction chamber as both a reactant and a chamber wall coolant;
means for introducing a second reactant into said secondary reaction chamber, in a zone laterally inwardly of the chamber wall coolant, for reacting

with the discharge products in such zone to cause a higher temperature reaction; and an annular liner in said secondary reaction chamber separating the higher temperature reaction zone from the chamber wall coolant; and wherein the means for introducing said discharge products into said secondary reaction chamber comprises a pervious wall having first openings leading to the zone inside said liner and second openings leading to the zone surrounding said liner.

6. The gas generator defined by claim 5, wherein the means for introducing a second reactant comprises an annular manifold inside said secondary reaction chamber and said pervious wall includes openings directed to introduce discharge products through said

manifold and openings directed to introduce discharge products into the space around said manifold, and said manifold includes discharge openings.

7. The gas generator defined by claim 5, wherein the means for introducing a second reactant includes a plurality of inlet pipes extending axially through the primary reaction chamber.

8. The gas generator defined by claim 7, wherein said inlet pipes are connected at their upstream ends to an upstream end portion of the motor and at their downstream ends to the said means for introducing the discharge products into the secondary reaction chamber, and such pipes function as structural supports.
